Primary Examiner — Paula Allen Greene

(74) Attorney, Agent, or Firm — Amin, Turocy & Watson,
LLP(57) **CLAIM**The ornamental design for an earphone, as shown and
described.

DESCRIPTION

FIG. 1 is a left and front perspective view of an earphone;
FIG. 2 is a front elevational view thereof;
FIG. 3 is a rear elevational view thereof;
FIG. 4 is a top plan view thereof;
FIG. 5 is a bottom plan view thereof;
FIG. 6 is a left side elevational view thereof; and,
FIG. 7 is a right side elevational view thereof.
The long dash-short dash broken line adjacent the shaded
areas represent the bounds of the claimed design while all
other broken lines depict portions of the earphone that form
no part of the claimed design.

1 Claim, 5 Drawing Sheets(56)
